DESIGN FOR A RADIAL SAW SUPPORT

Mearl V. Tracy, Pasadena, Calif.

Application November 22, 1946, Serial No. 135,014

Term of patent 14 years

(Cl. D93—3)

To all whom it may concern:

Be it known that I, Mearl V. Tracy, a citizen of the United States, residing at Pasadena, in the county of Los Angeles and State of California, have invented a new, original, and ornamental Design for a Radial Saw Support, of which the following is a specification, reference being had to the accompanying drawing, forming a part thereof.

Figure 1 is a perspective view of a radial saw support, looking toward one side thereof and showing my new design.

Figure 2 is a similar view of the radial saw support, but looking toward the opposite side thereof.

I claim:

The ornamental design for a radial saw support, as shown.

MEARL V. TRACY.
